CRIB ATTACHMENT FOR BEDSTEADS

Andrew S. Waters, Dallas, Tex., assignor of one-half to Josephine Shorter, Dallas, Tex.

Application July 31, 1943, Serial No. 496,865

1 Claim. (Cl. 5—95)

1

This invention relates to infants' beds or cribs and it has particular reference to a crib adapted to be displaceably attached to the foot of a conventional bedstead.

The principal object of the invention is to provide for the attachment of a baby bed or crib to a conventional bedstead in such manner that it will be most convenient for the occupant of the bed to attend the infant and the latter's crib is so disposed in relation to the larger bed that it will interfere in no way with the comfort of the occupants thereof.

Another object of the invention is to provide an infant's crib, attached as described to a conventional bed, with the further provision that it is capable of being shifted from a position over the foot portion of the bed to a position beyond the same so that it will be out of the way when the covering of the bed is to be straightened.

Still another object of the invention is to provide for further adjustment in the inoperative position of the crib attachment in that it may, if desired, be displaced to a position parallel with the foot board of the bed to which it is attached, by detaching the means by which it is supported in the other positions and when so inoperatively disposed, the crib may be used to store the bed clothing for the crib or other articles and suitably concealed.

With the foregoing objects as paramount, the invention has particular reference to certain features of accomplishment, to become manifest as the description proceeds, taken in connection with the accompanying drawing, wherein:

Figure 1 is a perspective view of a conventional bed, showing the crib attached thereto in a manner in keeping with the present invention.

Figure 2 is a detail view of the crib in transverse section, showing the means by which it is displaceably attached to a conventional bed, the latter being shown fragmentarily.

Figure 3 is a detail perspective view fragmentarily showing the crib and a portion of its mounting, and

Figure 4 is a detail view of one of the supporting links.

Continuing with a more detailed description of the drawing, reference is primarily made to Figure 1 wherein 10 denotes a conventional bedstead and bed of the type having posts 11 at both head and foot. The posts at the foot of the bed provide the supporting means for the crib 12 in the present case but it is obviously possible in cases where the design of the bed does not include posts, supporting risers to take the place of posts

55

2

can be affixed to the foot board of the bedstead without departing from the intent of the invention.

The crib 12 per se is not unlike the conventional crib and is adapted to be supported a sufficient height above the foot of the bed, when in operative position so that it will not interfere with free and unrestricted normal movement of the feet and legs of the occupants of the bed 10, yet will be accessible to one occupying the bed should the baby require attention during the night.

Mounted on the confronting sides of each of the foot posts 11 is a plate 13 having a collar or ferrule 14 affixed to its center. A rod 15 extends from one to the other of these collars and has its ends journaled therein. This rod serves to support the crib 12 at one side and, to facilitate movement of the crib from operative to the inoperative position shown in dotted lines in Figures 1 and 2, a roller 16 is mounted on the rod 15 near each end.

To constrain the crib 12 against other than lateral movement, a strap 17 is affixed to its underside near each end and so spaced from the underside of the crib that they will embrace the rollers 16 carried by the rod 15. It is apparent that the straps will prevent movement of the crib away from the rod under pressure imposed on the opposite side of the crib.

In support of the weight of the crib and its contents is a pair of link 18. One end of each link is provided with an aperture 19 (Fig. 4) to provide for its convenient attachment to the lower portion of the crib at one end intermediate the sides thereof. Suitable means such as a threaded pin 20 and wing nut 21 may serve to hold the end of the link in secure relation to the crib. The opposite end of the link 18 is slotted at a, which slot terminates near the end of the link in an enlargement b, shaped to define opposed recesses c.

The recesses c in the slot a are adapted to alternately receive a pin 22, mounted on a plate 23, in turn mounted on confronting sides of posts 11 below the rod mountings 13, when the crib 12 is in operative and inoperative positions. In other words, when the crib is positioned as shown in solid lines in Figures 1 and 2, the links 18 are so positioned that they will support the crib by having one recess c in engagement with the pin 22. However, when it is desired to shift the crib to the position shown in dotted lines in these figures, the upper ends of the links are detached from the crib, the latter is moved to the new

3

position and the links are again attached as before but the lower ends thereof are shifted so that the opposite recess *c* will engage the pin. Thus, the crib is supported in this new position just as securely as in the first position.

Should it be desired to move the crib 12 to still another position in the interest of conserving space, the links 18 may either be removed entirely or released from the cribs at their upper ends and allowed to assume a position parallel with the posts 11 and lower the crib to a position on its side when its bottom will be substantially parallel with the head board of the bed 10, as shown by the dotted lines below the first dotted position of the crib. In this third position, the crib may be used to store bed linens, covers and the like and suitably covered to present a slightly appearance.

It is apparent that in either of the two first positions of the crib shown in Figures 1 and 2, it may be in a position for use, the second position being of advantage should immediate conditions make it impracticable for the placing of the crib directly over the bed. However, generally it is intended for greater convenience for the attendant that the crib be arranged in the first or

4

solid line position during night periods, while the second dotted position shows the crib as being displaced to permit the covers of the bed 10 to be rearranged.

Manifestly, the construction as shown and described is capable of some modification and such modification as may be construed to fall within the scope and meaning of the appended claim is also considered to be within the spirit and intent of the invention.

What is claimed is:

A crib attachment for bedsteads comprising in combination with the foot posts of a bedstead, a rod extending horizontally between said foot posts, rollers mounted on said rod, a crib frame resting along one side on said rollers, straps extending transversely of said frame at the underside thereof near each end to constrain said crib to roll on said rollers within predetermined limits, a link detachably pivoted to each end of said crib and having slidible connection to said foot posts at a point below said rod to support said crib frame in adjusted positions forwardly and rearwardly of said foot posts.
